UNITED STATES PATENT OFFICE.

COLUMBUS U. MATSLER, OF PLAINVIEW, TEXAS.

COMBINATION-TOOL.

1,382,109.

Specification of Letters Patent. Patented June 21, 1921.

Application filed March 22, 1920. Serial No. 367,783.

To all whom it may concern:

Be it known that I, COLUMBUS U. MATSLER, a citizen of the United States, residing at Plainview, in the county of Hale and State 5 of Texas, have invented certain new and useful Improvements in Combination-Tools, of which the following is a specification, reference being had to the accompanying drawings.

10 This invention relates to combination tools and particularly to a combination tool for use in wire fence construction and repair, and has for its object to provide a device of this character, capable of driving staples, 15 pulling staples, cutting, and holding wire.

Another object is to provide a tool of this character having an extension on one end for use in stretching wire from one support to another, said extension having a slot in 20 which the wire is disposed and retained during the operation of the tool and from which it may be easily and quickly disengaged.

With these and other objects in view the invention consists in the improved construction 25 and arrangement of parts to be hereinafter more particularly described, fully claimed, and illustrated in the following drawings, in which:

Figure 1 is a side elevation of a combined 30 wire fence tool constructed in accordance with an embodiment of my invention;

Fig. 2 is an end plan view;

Fig. 3 is a side elevation of the device used 35 as a wire stretcher; and

Fig. 4 is a perspective view showing the position of the extension when wrapping the wire after the stretching operation.

Referring to the drawings, 5 designates one handle portion and 6 the other handle 40 portion of the tool. These handle portions are pivoted to each other adjacent one of their ends as at 7. The end portion 8 of the handle 5 includes a hammer member 9 which projects laterally from the end portion of the handle. The rear end 10 of the hammer is 45 concave and roughened, a pair of concave recesses 11 being formed in the rear end 10 of the hammer for the purpose to be herein-after described. The end portion 8 is also 50 provided with recesses 12 in each side thereof, the edges of said recesses being sharpened.

The end portion 13 of the handle portion 6 is enlarged, and provided with recesses 14, 55 which coöperate with the recesses 12 to provide wire cutters. The confronting inner

faces 15 of the handle portions 5 and 6 adjacent their enlarged ends are roughened and coöperate to serve as wire holding means. The end portion 13 includes a right-angular 60 extension 16, the rear surface 17 of which is concave and roughened to coöperate with the rear end 10 of the hammer. The rear end 17 is also provided with a pair of concave recesses 18 which register with recesses 11 in 65 the rear end 10 of the hammer. By this means a staple can be easily removed from an object, as the confronting surfaces 10 and 17 permit the staple to be firmly grasped. The hammer member 9 and extension 16 70 form a fulcrum adapted to engage a fence post or like support, whereby considerable force may be applied to the wire in the stretching operation.

The extension 16 has its end portion re- 75 duced to provide a wire stretching member or further extension 19, which tapers from the extension 16 and has its end portion bifurcated as at 20. A shoulder is formed at the junction of the extension 16 and the 80 member 19. It will be noted that the extension 16 and stretching member 19 extend from the side of the handle portion 6 at the end thereof so as to permit the user to use the tool without coming in contact with the 85 wire.

In operation, the end portion 1 of the wire 2 is passed through the loop 3 formed in the adjacent end of the wire 4. After passing the end portion 1 through the loop the ex- 90 tremity 4^a thereof is passed through the bifurcated end 20 and around one of the fingers formed by said bifurcation so as to prevent accidental disengagement of the end portion 1 from the member 19. Upon rota- 95 tion of the handle member of the tool the end portion 1 which is disposed between the loop 3 and the extremity 4^a will be wound upon the member 19. If this winding operation does not remove the kinks formed in 100 the wires 2 and 4, the member 9 may be engaged with an adjacent post or support and used as a fulcrum to further stretch the wire. After the end portion 1 of the wire 2 has been wound on the member 19 to such an 105 extent as to position the member 19 closely adjacent the loop 3 as shown in Fig. 3, the tool is then rotated with the member 19 disposed in a plane parallel to the wires 2 and 4 to unwind the end portion 1 of the wire 110 from the member 19 on to the wire 2, as shown in Fig. 4. This operation is con-

tinued until all of the coils on the member 19 are wound on the wire 2. The extremity 4^a is then removed from the finger or bifurcated portion of the member 19 and grasped 5 by the holding means 15 so as to permit said extremity to be wound around the wire 2 to eliminate projections. The holding means is then used to clench the extremity.

From the foregoing it will be readily seen 10 that this invention provides a novel combination tool which possesses the most of the tools necessary in wire fence construction and repair. An important feature of this tool is that the wire can be stretched and tied 15 without requiring a separate tool for these two operations, the holding means 15 assisting in the wrapping or tying operation to prevent the stretched wire from slipping.

What is claimed is:

A wire stretching tool of the character de- 20 scribed comprising a handle member having an enlarged extension on one end, said ex- 25 tension being disposed in right-angular re- 30 lation to the handle member, the outer end portion of the extension being reduced to provide a shoulder, said reduced portion tapering from said shoulder to the end of said reduced portion, said end being bifurcated for the reception of one end of a wire, where- 35 by said wire may be wound upon one of the fingers resulting from the bifurcation to prevent slipping.

In testimony whereof I hereunto affix my signature.

COLUMBUS U. MATSLER.
